Des. 210,806
Patented Apr. 16, 1968

210,806

PAIR OF SUNGLASSES OR THE LIKE

Atherton R. Mitchell, Dillon Beach, Calif., assignor to Renauld International, Ltd., Burlingame, Calif., a corporation of Delaware

Filed Jan. 31, 1967, Ser. No. 5,629

Term of patent 14 years

(Cl. D57—1)

FIG. 1

FIG. 2.

The top portion of the sunglass front is lined to indicate a decorative pattern.

I claim:

The ornamental design for a pair of sunglasses or the like, substantially as shown and described.
